UNITED STATES PATENT OFFICE.

ADAM BACH, OF CHICAGO, ILLINOIS.

DESIGN FOR A FORK-CROWN FOR BICYCLES.

SPECIFICATION forming part of Design No. 25,335, dated March 31, 1896.

Application filed February 6, 1896. Serial No. 578,284. Term of patent 31 years.

To all whom it may concern:

Be it known that I, ADAM BACH, a citizen of the United States, residing at Chicago, in the county of Cook and State of Illinois, have 5 invented and produced a new and original Design for Fork-Crowns for Bicycles, of which the following is a full and complete specification, reference being had to the accompanying drawings, in which—

10 Figure 1 is a front elevation of a fork-crown embodying my design. Fig. 2 is a sectional elevation of the same. Fig. 3 is a plan view of the same.

Referring to the drawings, the leading fea-

ture of my design consists in the novel shape 15 which I give to the crown, it being in cross-section an approximate hexagon, as shown in Fig. 2, the angles of the hexagon gradually disappearing where the crown is enlarged near its middle portion. 20

Having thus described my invention, I claim—

The design for a fork-crown for bicycles herein shown and described.

ADAM BACH.
